BY

Thos. A. S. S.
ATTORNEY

UNITED STATES PATENT OFFICE.

ALPHONSE VANDERDONCK, OF BROOKLYN, NEW YORK.

GRIPPING DEVICE.

1,362,905.

Specification of Letters Patent. Patented Dec. 21, 1920.

Application filed April 15, 1920. Serial No. 374,028.

To all whom it may concern:

Be it known that I, ALPHONSE VANDERDONCK, a citizen of the United States, residing at Brooklyn, in the county of Kings and 5 State of New York, have invented certain new and useful Improvements in Gripping Devices, of which the following is a specification, reference being had therein to the accompanying drawing.

10 My invention relates to improvements in clutching and gripping devices, and more particularly is adapted for use in gripping cables, ropes, or similar articles such as clothes lines.

15 In the accompanying drawings I have illustrated in Figure 1 in side elevation, partly broken away, and partly in section, one application of my invention. Fig. 2 is a view of the same at right angles showing the 20 device in full outline without the rope in position. Fig. 3 is a side elevation, partly broken away, illustrating a modification, and Fig. 4 is a view looking from right to left at Fig. 3.

25 Referring now more particularly to Figs. 1 and 2, it will be observed that the handle or body portion 5 terminates in oppositely facing teeth such as 6—6' and is provided with a pivoted cap 7 provided with recesses 30 8—8' the same being opened at one side as indicated at 9. In order to grip the rope, the same may be passed through the opening 9 or introduced through the end of the same, after which by taking hold of the handle

5 the same is firmly gripped between the 35 teeth and the recesses, if pulled rightwardly looking at Fig. 1, between the teeth 6' and the recess 8'; if leftwardly, looking at the same figure, between the teeth 6 and the recess 8. These teeth of course may be straight 40 instead of formed in opposing directions.

In the modifications shown in Figs. 3 and 4 an additional binding or gripping device comprising the spur 10 at the end of the weighted member 11 may be pivoted at 12 45 as shown, in which case the rope will be normally gripped until the weighted member is shifted; thus releasing the same due to the eccentric mounting of the spur 10.

Of course it will be understood that various modifications may be made without departing from the spirit of the invention as claimed.

I claim:

In a hand gripping device of the class described, a handle provided at one end with a gripping portion at the opposite end having teeth at opposite sides thereof, a pivoted recessed member adjacent thereto through which a rope is adapted to be passed whereby 60 when said handle is pulled in either direction, said rope is gripped between the teeth of said gripping portion and the recessed member at the side in the direction in which said handle is pulled. 65

In testimony whereof I hereunto affix my signature.

ALPHONSE VANDERDONCK.
